UNITED STATES PATENT OFFICE.

SHERMAN W. SCOFIELD, OF CLEVELAND, OHIO.

SAFETY DEVICE FOR PRESSES.

1,370,369.

Specification of Letters Patent.

Patented Mar. 1, 1921.

Application filed April 26, 1918, Serial No. 230,877. Renewed August 16, 1920. Serial No. 402,825.

To all whom it may concern:

Be it known that I, SHERMAN W. SCOFIELD, a citizen of the United States, resident of Cleveland, county of Cuyahoga, and State of Ohio, have invented new and useful Improvements in Safety Devices for Presses, of which the following is a specification, the principle of the invention being hereinafter explained and the best mode in which I have contemplated applying that principle, so as to distinguish it from other inventions.

My invention relates to safety devices and particularly to such devices adapted for use in connection with the operation of power presses. More particularly, my invention relates to a safety device whose function is to prevent the normal operation of the press when any foreign body, such as the hand of the operator, is disposed in or adjacent to the path of the downwardly moving press plunger. Specifically, the apparatus provides means furnishing a safety trip which functions only in the absence of such foreign body, the shop power being applied entirely independently of a treadle. The function of the safety trip herein disclosed is controlled by electrically-operated mechanism. The invention is illustrated in connection with the operation of power presses of both the positive clutch type and the automatic pin clutch type.

The annexed drawings and the following description set forth in detail certain means embodying my invention, such disclosed means, however, constituting but one of the various embodiments in which the principles of my invention may be used.

In said annexed drawings:

Figure 1 represents a broken side elevation of a standard power press of the positive clutch type to which my improved safety device has been applied; Fig. 2 represents a horizontal section taken in the plane indicated by the line II—II, Fig. 1, the punch and connected parts being omitted; Fig. 3 represents, upon an enlarged scale, a part of the elements shown in Fig. 1; Fig. 4 represents a vertical section taken in the planes indicated by the lines IV—IV, Fig. 3; Fig. 5 represents a section taken in the planes indicated by the lines V—V, Fig. 3; Fig. 6 represents, upon an enlarged scale, other elements shown in Fig. 1; Fig. 7 represents a broken side elevation of a standard power press of the automatic pin clutch

type to which my improved safety device has been applied; and Fig. 8 represents a section taken in the plane indicated by the line VIII—VIII, Fig. 7.

Referring to the annexed drawings, Figs. 1 to 6, inclusive, there are disclosed the base 1, and upper standards 2 of a positive clutch type of power stamping press provided with a table 3 upon which is mounted the die 4 adapted to coöperate with the vertically reciprocable punch 5. The latter is secured to a plunger 6 connected to the crank shaft 7 by a rod 8 connected to a crank (not shown). A continuously rotating fly-wheel 9 is coupled with or uncoupled from the crank shaft 7 by suitable well-known means, hereinafter more fully mentioned.

A guard 11 is secured to one end of a pair of arms 12 and 13 which are pivoted upon studs 12' secured in the standards 2, the arm 13 being extended rearwardly and carrying upon its other end a disk member 18, provided with a pin 18'; hereinafter more fully mentioned. A treadle connecting rod 15, secured to a treadle 10 which is pivoted at its rear end in the base 1, is provided at its upper end with a roller 16 adapted to contact with the arm 13 so as to raise or lower the same, as will be readily understood, said treadle rod 15 sliding in a bracket 15' secured to the standard 2 and being normally held in its upper position by means of a spring 17 which is put under tension by the downward actuation of the treadle 10. The guard 11, treadle 10 and connecting rod 15 constitute a controlling device whose function will be hereinafter fully described, the treadle 10 serving no other purpose and being independent of and not connected to the actuating mechanism which operates the press. The disk member 18 which is carried on the end of the rod 13 is adjustable upon the same through the provision of the slot 14. A bracket member 19 is secured to the standard 2 and provided with two contact fingers 19' which lie within the path of movement of the pin 18' of the disk member 18 and are forced into contact one with the other by the upward movement of said pin.

The clutch which operatively connects the fly-wheel 9 and crank shaft 7 ordinarily cannot be coupled because of the provision of a trip mechanism consisting of the rocker-arm 20 restrained by the arm 23, a construction furnishing a safety trip. A rocker-shaft 21 and rocker-

arm spring 22, which latter is under tension when the clutch mechanism is ineffective, are also shown. The removal of the restraining influence upon the rocker-arm 20, 5 by means hereinafter fully described, will result in the actuation of said arm 20 through the spring 22 to effect the coupling of the crank shaft 7 and fly-wheel. Said restraining member is represented by the 10 arm 23, as stated, which acts as a trip dog and is pivoted intermediately of its ends upon a bolt 25 which is mounted in a bracket 24 secured to the standard 2. Secured to one end of said arm 23 is a rod 26 intersecting the standard 2 and connected at its other end to an arm 27 pivoted to the member 28 secured to a base member 29 carried by the standard 2. Said member 27 is 15 provided with a member or surface portion 27' which, upon the energizing of a magnet 30, is adapted to be attracted by the latter, against the tension of a spring 26', which action, through the arm 27, and rod 26 will cause the dog 23 to release the rocker-arm 20, as shown in dotted lines in Fig. 5. Double wires 31 and 32 from a lamp socket or any other suitable source of electric power are disclosed, one of which is fastened to one of the contact fingers 19', and the other 20 fastened to one terminal of the magnet 30. A length of wire 33 is fastened to the other terminal on the magnet 30, the other end of this wire being fastened to the other contact finger 19'. The completion of the 25 circuit is effected when the guard 11 reaches the plane of the top of the table 3, this action taking place only if the guard meets no obstruction.

It is evident from the foregoing description 40 that the clutch which couples the crank shaft 7 to the fly-wheel 9 cannot be rendered effective until after the guard 11 contacts with the table 3. If, therefore, the guard 11 meets with any obstruction in its 45 downward movement, such as the hand of the operator, the electric circuit including the magnet 30 will not be completed, and the safety trip, which allows the operation of the clutch, will not function, so that the 50 plunger 6 cannot be effectively operated to the injury of the workman.

Figs. 7 and 8 illustrate the use of my improved safety trip in connection with a press of the automatic pin clutch type, a 55 "Toledo" press of well-known construction being shown, in which is shown the rod 34, the trip bracket 35, the trip 36, the clutch pin 37, the drive collar pin 38 and the trip spring 39. Connected to the outer end of 60 the rod 34 is one member of a rocker-arm 40 pivoted upon the frame 2 and the other member of which is connected to a rod 41 intersected and supported by a member 42 pivotally supported by two arms 27 in turn pivotally supported upon the outer end of the 65

member 28 connected to the frame 2 and supporting the magnet 30. It is evident from the accompanying drawing that the completion of the electric circuit and the energizing of the magnet 30 will cause a 70 member 27' mounted upon the arms 27 to be attracted by said magnet and this action through the arms 27 and rod 41 will rock the arm 40 and cause the trip 36 to be actuated so as to permit the plunger to effect its 75 downward movement.

It is very evident that the utilization of the principles of my safety trip allows the clutch mechanism of standard forms of presses to be utilized without any change 80 in construction or relative disposition of parts, the trip treadle and connecting rod being dispensed with.

What I claim is:

1. In a safety device for presses, the combination with the fly-wheel and crank-shaft; of means tending to induce their normal co-operative relation; means including a guard and electrically operated elements controlled by said guard for controlling the functioning of said inducing means; and means controlling the functioning of said guard. 85

2. In a safety device for presses, the combination with the plunger and die and means for causing the reciprocation of said plunger toward and from said die; of a detecting device, means controlling the functioning of the latter, electrically actuated means controlled by said device, and a safety trip controlling the functioning of said plunger-actuating means and in turn controlled by 95 said electrically operated means. 100

3. In a safety device for presses, the combination with the plunger and die, means tending to effect the reciprocation of said plunger toward and from said die, and means restraining the last mentioned means; of a controlling device consisting of a guard movable toward the die, a treadle and a connecting rod, and other means controlled by the movements of the guard and tripping said restraining means to permit said plunger-reciprocating means to function, the functioning of said permitting means being entirely independent of the power applied 110 to said treadle. 115

4. In a safety device for presses, the combination with the plunger and die and means for causing the reciprocation of said plunger toward and from said die; of a detecting device, means for moving the latter toward said die independently of said plunger, electrically actuated means controlled by the movements of said device, and a safety trip controlling the functioning of 120 said plunger-actuating means and in turn controlled by said electrically operated means. 125

5. In a safety device for presses, the combination with the plunger, die, fly-wheel, 130

- crank shaft, and clutch for coupling said shaft and wheel; of a controlling device consisting of a guard, a treadle, and a connecting rod, said guard being moved downwardly toward said die upon the actuation of said treadle, means preventing the coupling of said wheel and shaft, a magnet, a pivoted arm adapted to be actuated by the latter, means connecting said pivoted arm to said coupling-preventing means, the construction being such that the coupling-preventing means are rendered non-effective when the magnet is energized, and an electrical circuit within which said magnet is included, said circuit becoming closed upon the contact of said die and guard.
6. In a safety device for presses, the combination with the plunger, die, fly-wheel, crank shaft, and clutch for coupling said shaft and wheel; of a controlling device consisting of a guard, a treadle, and a connecting rod, said guard being moved downwardly toward said die upon the actuation of said treadle, means preventing the coupling of said wheel and shaft, a magnet, a pivoted arm adapted to be actuated by the latter, means connecting said pivoted arm to said coupling-preventing means, the construction being such that the coupling-preventing means are rendered non-effective when the magnet is energized, and an electrical circuit within which said magnet is included, said circuit becoming closed upon the contact of said die and guard, the resultant actuation of the plunger being entirely independent of the power applied to said treadle.
7. In safety devices for presses, the combination with a fly-wheel and crank shaft of the press and a holding device which until tripped is adapted to hold said shaft out of operative engagement with said wheel; of movable guard means, means for effecting said movements, electrically actuated means for tripping said holding device to allow the engagement of said wheel and shaft, said tripping means functioning only when the normal movement of the guard has taken place; and means effecting said functioning.
8. In a safety device for presses, the combination with the plunger and die and means for causing the reciprocation of said plunger toward and from said die; of a guard, means for moving the latter toward said die independently of said plunger, said guard being caused to reach said die in advance of said plunger, restraining means preventing the downward movement of the plunger, electrically actuated means for tripping the restraining means, said electrically actuated means becoming effective upon the contact of said die and guard; and means for causing said effective action.
9. In a safety device for presses, the combination with the plunger and die; of a guard, means for moving the latter toward said die independently of said plunger, said guard completing its downward movement before the plunger commences its downward movement, means for effecting such plunger movements restraining means preventing the downward movement of the plunger, electrically-actuated means rendered effective upon the contact of the die and the guard for tripping the restraining means; and means for causing said effective action.
10. In a safety device for presses, the combination with the plunger and die and means for causing the reciprocation of said plunger toward and from said die; of a guard, means for moving the latter toward said die independently of said plunger, means rendering the plunger ineffective, electrically-actuated means adapted to nullify the restraining action of said last-named means, and means causing said electrically-actuated means to function at the moment of contact of said guard and said die.
11. In a safety device for presses, the combination with the plunger and die, means for reciprocating said plunger, and a suitable table for said die; of a guard movable toward and from said table, means for effecting such movements independently of the plunger, means rendering the plunger ineffective, electrically actuated means adapted to nullify the restraining action of said last-named means, the construction being such that an obstruction in the path of movement for said guard to said table prevents the functioning of said electrically actuated means; and means causing the latter to function at the moment of contact of said guard and said table.

Signed by me, this 6th day of April, 1918. 105
SHERMAN W. SCOFIELD.
